UNITED STATES PATENT OFFICE.

WILLIAM G. MOFFET, OF CHICAGO, ILLINOIS.

VENDING-MACHINE.

1,047,549.

Specification of Letters Patent. Patented Dec. 17, 1912.

Application filed May 23, 1912. Serial No. 699,153.

To all whom it may concern:

Be it known that I, WILLIAM G. MOFFET, a citizen of the United States, residing at Chicago, in the county of Cook and State of Illinois, have invented a new and useful Improvement in Vending-Machines, of which the following is a specification.

My invention relates, more particularly, to machines for vending newspapers; and my object is to provide a simple construction of vending machine for the purpose stated, which shall be economical of manufacture, be positive in operation, and in which danger of clogging of the papers is avoided; and generally to improve upon machines as hitherto provided to the end of rendering them better adapted to perform their functions.

Referring to the accompanying drawings—Figure 1 is a view in vertical sectional elevation of a machine constructed in accordance with my invention, showing the machine in normal, closed condition, the section being taken at the line 1 on Fig. 5 and viewed in the direction of the arrow. Fig. 2 is a view like Fig. 1, showing the parts of the machine in the position they occupy when actuated to deliver a newspaper. Fig. 3 is a section taken at the line 3 on Fig. 5 and viewed in the direction of the arrow, showing newspapers in the machine for delivery therefrom and the parts of the machine in the positions they normally occupy. Fig. 4 is a view like Fig. 3, showing the parts in the positions they occupy when delivering a newspaper. Fig. 5 is a plan section taken at the line 5 on Fig. 1 and viewed in the direction of the arrow, this view showing the parts of the machine in a position corresponding to that illustrated in Figs. 2 and 4. Fig. 6 is a broken section taken at the line 6 on Fig. 5 and viewed in the direction of the arrow; and Fig. 7, a broken section taken at the line 7 on Fig. 5 and viewed in the direction of the arrow.

The casing of the machine, which may be constructed of any suitable material, as for example, sheet-iron, is represented at 8 and 50 contains a false-bottom 9 and partitions 10 reaching short of said false-bottom and forming therewith and with the front and rear sides of the casing, a compartment 11 serving as a magazine for the newspapers 55 to be delivered by the machine. The front

side 12 of the casing 8, by preference, is fitted with a plate 13 of glass, through which the interior of the magazine 11 may be viewed, and contains a horizontally-extending slot 14 of a width slightly greater than the length of the newspapers, when folded as hereinafter described, and in which condition they are charged into the magazine 10.

The rear portion of the magazine 11 contains a flanged plate 15 which extends lengthwise of the machine and is spaced from the false-bottom 9, as represented in Figs. 2 and 3, the plate 15 forming a ledge upon which the newspapers to be delivered by the machine and represented at 16, are supported at their rear edges (Figs. 2 and 3), the newspapers 16 for delivery by the mechanism hereinafter described being so folded as to present rearwardly turned edge-portions 17 at the front edges thereof, and in which condition they are deposited in the magazine 11 in stacked condition, as represented of those illustrated in the drawings, the lowermost one of the papers resting at its rear-portion upon the ledge 15 and its rearwardly-turned edge-portion 17 being unsupported excepting as it may bear against the bottom 9 of the magazine 10, thereby causing the portion 17 of the lowermost paper 16 to spring downwardly and assume the position illustrated in Fig. 3, for engagement by the delivery mechanism, of which the following is a description.

Located in the space between the plate 15 and the false-bottom 9 and extending lengthwise of the casing 8 are upper and lower plates 18 and 19, respectively, each substantially of the same depth as the plate 15, as represented. The plates 18 and 19 are adapted to be telescoped with each other, as represented in Fig. 3 and as hereinafter described, to withdraw them from the path of movement of the portions 17 of the papers 16 as said portions spring down to the position illustrated in Fig. 3 and as hereinbefore described. The plates 18 and 19, operated as hereinafter described to discharge the papers 16 through the slot 14 for delivery from the machine, are guidedly supported, to move horizontally, in grooves 20 formed in the inner surfaces of the partitions 10 at their lower ends, and disposed midway vertically of the top and bottom of the discharge-slot 14; the upper plate 18 which is

of slightly less length than the distance between said partitions, and rests at its forward edge upon the plate 19, being provided at opposite ends with laterally extending upwardly-deflected lugs 21 which extend into the grooves 20 and at which it is supported therein, and containing transversely extending slots 22 toward its opposite ends, into which headed pins 23 carried on the upper surface of the plate 19 extend, whereby the telescoping of the plates 18 and 19, and extension thereof may be effected as and for the purpose herein-after explained.

15 In the operation of the machine the plates 18 and 19 are caused to be projected forwardly from the folded or telescoped condition represented in Fig. 3 to the condition illustrated in Fig. 4 for discharging a paper 16 through 20 the slot 14, the plate 19 in this operation entering, at its forward edge, the hook-portion of the paper 16 formed by the rearwardly turned edge 17 and forcing the paper forward, a description of the preferred 25 means for thus operating the plates 18 and 19 being as follows: Journalized in lugs 24 on the base of the casing 8 is a shaft 25 equipped with a pair of upwardly-extending arms 26 spaced apart and rigidly secured 30 thereto, the arms 26, which are located in the casing 8 in the spaces between the casing-sides and the partitions 10, being connected by links 27 with the plate 19. The links 27 for this purpose are pivotally connected at their rear ends, as indicated at 28, 35 to clips 29 secured to the under sides of the plate 19 at opposite ends of the latter near its rear edge and extending under and at the outside of the partitions 10 as represented, 40 and at their forward ends being pivotally connected, as indicated at 30, to the upper ends of the arms 26, whereby upon swinging the arms 26 to the left in Fig. 3 from the position therein illustrated to the position 45 illustrated in Fig. 4, by rotating the shaft 25 to the left in Fig. 3, the plate 19 will be projected to the left in Fig. 3 and through the slot 14, and by reason of its said slot and pin connection with the 50 plate 18 will cause the latter to move with the plate 19 as represented in Fig. 4, and when shaft 25 is rotated in the opposite direction to return the arms to the position represented in Fig. 3 the plates 18 and 19 55 will be telescoped and extend beneath the ledge 15, as represented in said last-mentioned figure.

In machines of this general character provision is made for the operation of the machine only upon the introduction therein of a coin, or other token. Any suitable means for coöperation with the drive-shaft 24 for the above stated purpose may be provided, a description of those illustrated being as 60 follows: Journalized on an end of the shaft

25 is a sleeve 31 equipped at its outer end with an operating crank-handle 32 and intermediate its ends with an upwardly-extending arm 33 fixed thereto. The inner end of the sleeve 31, which contains a peripheral 70 annular groove 34, extends into a boss 35 provided on the adjacent one of the arms 26, said boss carrying a pin 36 which extends into the groove 34 for preventing accidental withdrawal of the handle 32 from the shaft 75 25. The upper end of the boss-equipped arm 26 is provided on a face thereof with laterally-extending lugs 37 and 38 spaced apart a distance considerably in excess of the diameter of the coin, as for example, 80 that indicated at 39, with which it is intended that the operation of the machine be controlled. The arm 33 is equipped at its upper end with upper and lower lugs 40 and 41, respectively, which project into the space 85 between the lugs 37 and 38 and engage with the front face of the lug 38 which forms a stop for the arm 33 when the parts of the machine are in normal position (Fig. 1), and through the medium of which the shaft 90 24 and parts connected therewith are returnable to normal position, lugs 40 and 41 being spaced apart a distance sufficient to cause them to pass by the lug 37, above and below the latter, without engaging therewith, when the shaft 25 is rotated to the left in Fig. 1, and thus the shaft 25 will not be turned unless a coin or other token is introduced into engagement with the lugs 37, 40 and 41, as 95 hereinafter described.

The parts just described are so proportioned and arranged that the distance between the lugs 37, 40 and 41, when the parts are in normal position, is slightly greater than the diameter of the coin 39. The coins 105 39 are adapted to be fed to the operating mechanism described through a chute 42, which opens at its upper end, through the front side of the casing 8 as represented at 43, and terminates at its lower end in a discharge-opening 44 so disposed that a coin deposited into the chute will drop into the space between the lugs 37, 40 and 41, and rest against the spring arm 45, secured to the casing (Fig. 1) whereby upon rotating 110 the shaft 25 to the left in Fig. 1, the coin 39, by reason of its interposition between the lugs 37, 40 and 41, will cause the arms 26 to be swung to the left in said last-named figure and operate the paper-discharging 115 plates 18 and 19 as hereinbefore described, the coin 39, upon the act of rotating the shaft 25 in the opposite direction to return the parts to normal position, after the paper-delivering operation, dropping to the 120 bottom of the casing 8.

It is desirable that means guarding the interior of the machine against access through the discharge-slot 14 thereof, be provided, and to this end I provide upper 125

and lower yoke-shaped members 46 and 47, respectively, which are pivoted at their rear ends, as indicated at 48 and 49, to lugs 50 on the interior of the casing and are operated automatically to move them up and down, respectively, (Fig. 2) to permit a paper to be discharged through the slot 14 when the plates 18 and 19 are projected forwardly, as hereinbefore described, and to move them to slot-closing condition (Fig.

10 1) upon the act of retracting the plates 18 and 19. The means for thus operating the members 46 and 47 comprise plates 51 located at opposite ends of said members and pivoted between their ends, as indicated at 52, to depending brackets 53 secured to the partitions 10, the plates 51 being connected, in front of the brackets 53, with the upper member 46 by links 54 pivotally connected with the member 46, and plates 51, as indicated at 55 and 56, respectively, and in the rear of said brackets 53 with the lower member 47 by links 57 pivotally connected with the member 47 and plates 51, as indicated at 58 and 59, respectively.

25 The under sides of the plates 51 present rear, arc-shaped surfaces 60 concentric with the shaft 25 and downwardly-extending, front cam-surfaces 61, at which surfaces the plates coöperate with rollers 62 carried by the arms 26, said rollers in the oscillation of the arms 26 rolling along said surfaces and operating to oscillate the plates 51, by engagement alternately with the surfaces 61 and 60 to separate the yokes 46 and 47 by swinging them in opposite directions when the arms 26 are swung to the left in Fig. 1 for discharging a paper through the slot 14, and bring them together to close the slot 14 when the arms 26 are swung in the opposite direction to withdraw the plates 18 and 19 to the position represented in Fig. 3.

30 The following described operation of the machine will be manifest from the foregoing description.

To operate the machine, assuming the magazine 9 to contain papers 16 folded and stacked therein, as hereinbefore described, and that the parts of the machine are in their normal positions illustrated in Figs. 1 and 3, a coin 39 of the desired denomination is dropped into the slot 43, the coin thus deposited passing through the chute 55 42 and lodging on the spring arm 45 and between the lugs 37, 40 and 41. The operator then swings the handle 32 to the left in Figs. 1 and 3, with the result of swinging the arms 26 to the left in said figures and causing the plates 18 and 19 to be projected to the left therein for engaging with a paper, as hereinbefore described, and advancing it through the slot 14, from which it may be readily withdrawn by hand, the yokes 46 and 47, during the said operation of the

arms 26, separating to the position illustrated in Fig. 2, to permit the slot 14 to become uncovered for passage of the paper therethrough. The engagement of the lugs 40 and 41 on the arm 33 with the lug 28 on the arm 26, operates to return the parts of the mechanism operated from the shaft 25, to normal position (Figs. 1 and 3), upon swinging the handle 32 to the right in Figs. 2 and 4.

35 It will be noted that not only is mechanism constructed in accordance with my invention simple and economical of manufacture, but it is rendered positive in its operation, and there exists no danger of clogging of the papers therein.

40 While I have illustrated and described a specific construction constituting an embodiment of my invention, I do not wish to be understood as intending to limit it to said construction, as the same may be variously altered and modified without departing from the spirit of my invention.

45 What I claim as new, and desire to secure by Letters Patent, is—

50 1. In a vending machine of the character described, the combination of a casing adapted to receive the articles to be vended, each folded to present a flange, said casing containing a delivery-opening, means for engaging with the flanges on said articles to deliver them to said opening, comprising relatively movable members guidedly supported opposite said opening, means connected with one of said members for moving it toward said opening, and means operated by the one of said members to which said actuating means are connected, operating after the initial movement of said last referred to member to advance therewith the other of said members toward said opening, for the purpose set forth.

55 2. In a vending machine of the character described, the combination of a casing adapted to receive the articles to be vended, each folded to present a flange, said casing containing a delivery-opening, means for engaging with the flanges on said articles to deliver them to said opening, comprising relatively movable members, one of which contains an elongated longitudinally extending slot and the other thereof is equipped with a pin extending into said slot, said members being guidedly supported opposite said opening, and means engaging with one of said members for moving it toward said opening, said slot and pin being so disposed as to cause the other of said members to be advanced toward said delivery-opening after the initial movement of, and together with, the one of said members to which said actuating means are connected, for the purpose set forth.

60 3. In a vending machine of the character described, the combination of a casing

- adapted to receive the articles to be vended each folded to present a depending flange, said casing containing a delivery opening, and means for engaging with the flanges on 5 said articles to move them into said opening comprising relatively-movable guidedly-supported members, and means for actuating both of said members, for the purpose set forth.

10 4. In a vending machine of the character described, the combination of a casing adapted to receive the articles to be vended each folded to present a depending flange, said casing containing a delivery opening, 15 a slide for engaging with the flanges on said articles to move them into said opening comprising upper and lower relatively-movable members opposing said opening, and means for actuating said members, for 20 the purpose set forth.

5. In a vending machine of the character described, the combination of a casing adapted to receive the articles to be vended each folded to present a depending flange, 25 said casing containing a delivery opening, a slide for engaging with the flanges on said articles to move them into said opening comprising upper and lower members, and means connected with one of said members 30 for moving them toward said opening and into engagement with the flange of the lowermost article, for the purpose set forth.

6. In a vending machine of the character described, the combination of a casing 35 adapted to receive the articles to be vended and folded to afford depending flanges, said casing containing a delivery-opening, a support for the articles extending partway across said casing to be spaced from said 40 delivery-opening, a slide formed of relatively movable members extending below said support and operating to engage with the flanges on said articles and deliver them in succession to said opening, means connected 45 with one of said members for moving it toward said delivery-opening, and means operated by the one of said members to which said actuating means are connected, operating after the initial movement of said last 50 referred to member to advance therewith the other of said members toward said opening, said slide being retractable to a position in which it will not obstruct the descent of the flanged portions of the articles.

55 7. In a vending machine of the character described, the combination of a casing adapted to receive the articles to be vended and folded to afford depending flanges, said casing containing a delivery opening, a support for the articles extending part-way 60 across said casing to be spaced from said delivery opening, means for engaging with the flanges on the articles to discharge the latter through said opening, comprising reciprocal relatively-movable members 65 guidedly-supported to extend below said support, and means for reciprocating said members.

8. In a vending machine of the character described, the combination of a casing 70 adapted to receive the articles to be vended and folded to afford depending flanges, said casing containing a delivery opening, a support for the articles extending part-way across said casing to be spaced from said delivery opening, upper and lower movable plates located below said support and opposing said opening, means for guiding said plates, means operatively connected with one of said plates for projecting it toward 75 said opening and into engagement with the flange on the lowermost article, and means for actuating the other of said plates from the one connected with said actuating means, for the purpose set forth.

9. In a vending machine of the character described, the combination of a casing 80 adapted to receive the articles to be vended and folded to afford depending flanges, said casing containing a delivery opening, a support for the articles extending part-way across said casing to be spaced from said delivery opening, upper and lower plates located below said support and guidedly supported opposite said opening, a suitably-journalized rock-shaft equipped with arms, links connecting said arms with one of said plates for removing the latter toward said opening and into engagement with the flange of the lowermost article, and means 90 for moving the other of said plates during the final movement of said flange-engaging plate.

10. In a vending machine, the combination with its casing, containing an article-discharge opening and adapted to receive the articles to be vended, of means for delivering the articles in succession to said opening, guard means for said opening comprising upper and lower yoke-shaped members pivotally connected at their lateral portions on said casing and extending at their intermediate portion adjacent to said opening, and means operating automatically upon actuating said article-feeding means to discharge an article into said opening, to 100 actuate said yoke-shaped members in opposite directions to spread them apart and uncover said opening and to swing said members toward each other to close said opening upon the act of returning said article-delivering means to normal position.

11. In a vending machine, the combination with its casing containing an article-discharge opening, of means for delivering the articles in succession to said opening, guarding-means for said opening pivotally connected with said casing, and a pivotally supported cam-equipped member operatively connected with said guard means and 110

engageable at its cam-portion by said article-delivering means, for the purpose set forth.

12. In a vending machine, the combination with its casing containing an article-discharge opening and adapted to receive the articles to be vended, of means for discharging the articles in succession to said opening, guard means for said opening comprising upper and lower pivotally-connected members adapted when in one position to close said opening and when moved from said position to uncover said opening, a pivotally-supported cam-member adapted to be engaged at its cam-portion by said article-delivering means, and means operatively connecting said cam member with said guard-plates for moving the latter in opposite directions when said cam-equipped member is actuated, for the purpose set forth.

13. In a vending machine, the combination with its casing, containing an article-discharge opening and adapted to receive the articles to be vended, of means for delivering said articles in succession to said opening, and guard means for said opening comprising upper and lower pivotally-supported plates, serving when in one position to close said opening and when moved from such position to uncover it, a cam-equipped member pivotally supported between its ends and adapted to be oscillated by engagement of said article-delivering means therewith, and means connecting said cam-equipped member with said plates at opposite sides of the point at which said cam-equipped member is pivotally supported, for the purpose set forth.

14. In a vending machine, the combination with its casing, containing an article-discharge opening and adapted to receive the articles to be vended, of means for delivering said articles in succession to said opening, guard means for said opening comprising a guarding-device for said opening, a pivotally-supported cam-member operatively connected with said device, and means for operating said cam-member from said article-delivery means, the whole being constructed and arranged to cause said device to be moved to uncover said opening when said article-delivering means are actuated to deliver an article, and be moved to close said opening when said last-named means are actuated to reposition the latter for the next delivery and to cause said device to be locked against movement in a direction to uncover said opening when said article-delivering means are retracted.

15. In a vending machine, the combination with its casing containing an article-discharge opening, of means for delivering the articles in succession to said opening, including a rock-member, a guarding device

for said opening, a pivotally-supported member provided with an arc-shaped surface concentric with the axis of said rock-member and terminating in a surface tangential to said arc-shaped surface, and means on said rock-member engaging with said arc-shaped and tangential surfaces of said pivotally-supported member for oscillating the latter, for the purpose set forth.

16. In a vending machine, the combination with its casing containing an article-discharge opening, of means for delivering the articles in succession to said opening, including a rock member, pivotally-supported upper and lower plates in said casing forming a guard-device for said opening, a pivotally-supported member provided with an arc-shaped surface concentric with the axis of said rock member and terminating in a surface tangential to said arc-shaped surface, and means on said rock member engaging with said arc-shaped and tangential surfaces on said pivotally-supported member for oscillating the latter, for the purpose set forth.

17. In a vending machine, the combination with its casing containing an article-discharge opening, of means for delivering the articles in succession to said opening, including a rock member, pivotally-supported upper and lower plates in said casing forming a guard-device for said opening, a member pivotally-supported between its ends and provided with an arc-shaped surface concentric with the axis of said rock member and terminating in a surface tangential to said arc-shaped surface, means connecting said last-named member with said plates at opposite sides of the point of pivotal support of said member, and means on said rock-member engaging with said arc-shaped and tangential surfaces of said pivotally-supported member for oscillating the latter, for the purpose set forth.

18. In a vending machine of the character described, the combination of a casing adapted to receive articles to be vended and folded to form flanges, said casing containing a delivery-opening, a member against which the articles bear, said member extending partway across said casing to be spaced from said delivery-opening and extending short of the flanges on said articles, a slide formed of relatively movable members located at the side of said support opposite to that engaged by said articles and operating to engage with the flanges on said articles and deliver them in succession to said opening, means connected with one of said members for moving it toward said delivery-opening, and means operated by the one of said members to which said actuating means are connected, operating after the initial movement of said last referred to member to advance therewith the

- other of said members toward said opening, said slide being retractable to a position in which it will not obstruct the flanges on said articles, for the purpose set forth.
- 5 19. In a vending machine, the combination with its casing containing an article-discharge opening and adapted to receive the articles to be vended, of means for delivering the articles in succession to said
- 10 opening, guard means for said opening comprising upper and lower members extending, when in normal condition, across said opening to close the latter, and means operating automatically upon actuating said article-feeding means to discharge an article into said opening, to actuate said guard members in opposite directions to spread them apart and uncover said opening and to swing said members toward each other to close said opening upon the act of returning said article-delivery means to normal position.
- 15 20. In a vending machine, the combination with its casing containing an article-discharge opening and adapted to receive the articles to be vended, of means for discharging the articles in succession to said opening, guard means for said opening comprising upper and lower members extending when in normal condition across said opening to close the latter, and when moved from said position to uncover said opening, a pivotally supported cam-member adapted to be engaged at its cam-portion by said article-delivery means, and means operatively connecting said cam-member with said guard members for moving the latter in opposite directions when said cam-equipped member is actuated for the purpose set forth.
- 25 30 35 40 21. In a vending machine, the combination with its casing containing an article-discharge opening and adapted to receive the articles to be vended, of means for discharging the articles in succession to said opening, guard means for said opening comprising upper and lower members supported to be movable toward and away from each other and adapted when in one position to close said opening, and when moved from said position to uncover said opening, a rock member, means connecting said rock member with said guard members for moving the latter in opposite directions when said rock member is actuated, and means operated by said article-delivery mechanism for rocking said rock member for the purpose set forth.
- 45 50 55 60 65 70 75 22. In a vending machine, the combination with its casing containing an article-discharge opening and adapted to receive the articles to be vended, of means for delivering said articles in succession to said opening, guard means for said opening comprising a movable guard device, a rock member connected with said guard device and provided with a plurality of bearing surfaces, and means, operated from said article-delivery means, and movable against said surfaces and from one of said surfaces to the other thereof, for rocking said rock member, the whole being constructed and arranged to cause said guard device to be moved to uncover said opening when said article-delivery means are actuated to deliver an article, and be moved to close said opening when said last-named means are actuated to re-position the latter for the next delivery and to cause said device to be locked against movement in a direction to uncover said opening when said article-delivery means are retracted.

WILLIAM G. MOFFET.
